UNITED STATES PATENT OFFICE

129,757

DESIGN FOR A CIGARETTE HOLDER

Charles H. Flaxbaum, New York, N. Y.

Application August 14, 1941, Serial No. 102,838

Term of patent 7 years

To all whom it may concern:

Be it known that I, Charles H. Flaxbaum, a citizen of the United States of America, residing at 514 West 110th Street, city, county, and State of New York, have invented a new, original, and ornamental Design for a Cigarette Holder, of which the following is a specification, reference being had to the accompanying drawing, forming a part thereof.

Fig. 1 is a front elevational view of a cigarette holder showing my new design.

Fig. 2 is a side view thereof.

I claim:

The ornamental design for a cigarette holder, as shown.

CHARLES H. FLAXBAUM.
